UNITED STATES PATENT OFFICE.

ARTHUR B. KLEIN, OF COVINGTON, KENTUCKY.

MEDICATED ARTICLE.

977,635.

Specification of Letters Patent.

Patented Dec. 6, 1910.

Application filed April 10, 1908. Serial No. 426,354.

To all whom it may concern:

Be it known that I, ARTHUR B. KLEIN, a citizen of the United States, residing at Covington, in the county of Kenton and State of Kentucky, have invented new and useful Improvements in Medicated Articles, of which the following is a specification.

The invention relates to an improvement in medicated articles and is more particularly directed to a cigar structure made up of the usual filler and wrapper in which a medicament is concealed to permit the effects thereof reaching the smoker during the consumption of the cigar.

15 It has been heretofore proposed to supply articles, such as cigarettes or the like with a certain proportion of medicament but experience has demonstrated that owing to the necessity of mixing this medicament with 20 the granulated tobacco with which the cigarette is made, an even distribution of the medicament is practically impossible, so that cigarettes made up of the particular impregnated material will vary in the proportion of 25 medicament.

The present invention is designed more particularly to obviate these objections and to put within the reach of the smoker a medicated cigar which can be relied upon to contain an exact proportion of the desired materials.

The present invention is illustrated in the accompanying drawings, in which:—

Figure 1 is a longitudinal sectional view 35 of a cigar made up in accordance with the invention. Fig. 2 is a transverse section thereof. Fig. 3 is a longitudinal section of a cigar made up in slightly modified form, and Fig. 4 a transverse section thereof.

40 Referring particularly to Figs. 1 and 2 of the drawings the cigar 1 is made up in the usual manner containing a filler 2 and wrapper 3. In this form the medicament desired to be used is made up in the form of a stick 45 or rod 4, preferably by compressing the va-

rious materials into the form desired. This medicated stick or rod is inserted centrally in the filler and entirely inclosed by the same.

In Figs. 3 and 4 a slightly modified form 50 is shown wherein the medicament 5 is in ground form and contained within a readily combustible envelop 6, as of tissue paper or even a section of cigar wrapper.

In both of these forms it will be noted that 55 the medicated strip is entirely inclosed within the cigar, so that in the initial lighting of the cigar the flame meets the tobacco only, thereby insuring a proper and perfect lighting. Furthermore, the medicated portion 60 except as noted extends throughout the entire length of that cigar desired to be consumed, so that during the entire smoking operation the fumes engendered in the consumption of the medicament reach the throat 65 and respiratory passages of the smoker in an even and continuous manner.

The particular and special function of the present invention is in the treatment and relief of diseases of the respiratory 70 passages, as catarrh, hay-fever, asthma and the like, and the particular ingredients used in connection with the same are stramonium, anise seed, cubeb berries, nitrate of potash, etc.

Having thus described the invention what is claimed as new, is:—

A cigar comprising the usual filling of tobacco and a wrapper, and a slender medicated body inclosed centrally within the 80 filling of tobacco and terminating a short distance from each end thereof and comprising a medicament in finely divided form inclosed in a combustible wrapper.

In testimony whereof I affix my signature 85 in presence of two witnesses.

ARTHUR B. KLEIN.
